CALENDAR

Abraham J. Spinner, Chicago, Ill., assignor to
 Plastic Binding Corporation, Chicago, Ill., a corporation of Delaware

Application August 22, 1938, Serial No. 226,056

6 Claims. (Cl. 40—119)

The invention relates generally to a wall calendar and more particularly to a binding and locking arrangement therefor.

A general object of the invention is to provide a calendar of the wall type having a binding and locking arrangement of new and improved construction.

A more particular object of the invention is to perfect a calendar of the loose-leaf type having binding means for the leaves of the calendar which means also serves as part of a locking means for the cover of the calendar.

Another object is to perfect a loose-leaf calendar of the wall type having a back cover and a front cover, binding elements secured to the back cover for suspending the leaves of the calendar below the covers, and means on the front cover cooperating with the binding elements to form locking means readily disengageable to permit a leaf to be turned and hidden underneath the front cover, and readily engageable to lock the cover to hold the leaf in turned position.

Other objects and advantages will become apparent from the following detailed description taken in connection with the accompanying drawing, in which:

Fig. 1 is a perspective view of a calendar embodying the features of the invention, showing the front cover of the calendar raised to permit the turning of a leaf of the calendar.

Fig. 2 is an enlarged fragmentary front elevational view, partially in elevation and partially in section, of the calendar shown in Fig. 1.

Fig. 3 is an enlarged fragmentary sectional view taken approximately along the line 3—3 of Fig. 2.

Fig. 4 is a view of the same proportion as Fig. 3, taken approximately along the line 5—5 of Fig. 2 but showing the front cover just engaging the binding elements.

Fig. 5 is an enlarged sectional view taken approximately along the line 5—5 of Fig. 2 and showing the front cover fully engaged or locked with the binding elements.

While the invention is susceptible of various modifications and alternative constructions, it is here shown and will hereinafter be described in a preferred embodiment, but it is not intended that the invention is to be limited thereby to the specific construction disclosed, but it is intended to cover all modifications and alternative constructions falling within the spirit and scope of the invention as defined by the appended claims.

Generally the calendar is of the type intended to be hung on a wall and is also of the type in which

the leaves of the calendar are intended to be employed for record purposes, and thus are to be saved and not torn off and thrown away after the month represented thereon has passed. Accordingly, the calendar comprises a back cover 10, a front cover 11 and a plurality of leaves 12. The covers as well as the leaves are of rectangular shape having their horizontal dimension greater than their vertical dimension, and with the leaves 12 both slightly shorter and slightly narrower in 10 order that they may be received between the covers 10 and 11, and when so received completely concealed between the covers. The front cover 11 is hingedly connected at its upper end to the upper edge of the back cover 10, while its lower edge is free, in fact, the covers 10 and 11 preferably are formed, as shown in Figs. 1 and 2, from a single piece which is bent midway of the longitudinal edges of the covers to form the hinged connection between the covers. If desired, an aperture 13 may be formed in the covers near the upper edges to receive a hook or nail by means of which the calendar is hung.

A unique binding arrangement is provided herein which serves not only as a means for securing the leaves in loose-leaf manner to the back cover, but also forms part of a locking means for the lower edge of the front cover. To that end, the back cover 10 near its lower edge is formed with a pair of closely spaced apertures 14 adjacent each end of the cover. Similarly, each leaf 12 is formed with a pair of apertures 16 formed in the leaves near the top edge and adjacent each end of the leaf. Adapted to be threaded through the apertures in the back cover 10 and the leaves 12 is a removable binding element, generally designated 17. In the present instance, this element comprises a pair of rings 18 secured together by a connecting portion 19. Each of the rings has its free end overlapping the connecting portion, as best seen in Figs. 3 to 5, and is resilient to permit the opening of the ring by distortion so as to permit its being threaded through the apertures 14 and 16. This binding element preferably is formed of plastic material, but may be formed of other materials having the desired degree of resiliency.

It is believed apparent from the foregoing description that the leaves 12 are normally suspended below the cover portions 10 and 11, as best shown in Fig. 1. When the end of a month or other unit of time represented on each leaf has been reached, the leaf may be turned upwardly so as to be received between the front and back covers, thus to be preserved for future reference.

and at the same time to be concealed from view. Such turning of a leaf is readily accomplished simply by lifting the front cover 11.

In order that the front cover 11 may retain the leaves which have been turned between it and the back cover, and in order that the weight of such turned leaves may not open the front cover a sufficient distance to permit the leaves to fall down, means is provided on the front cover for cooperation with the binding elements 17 forming a readily engageable and disengageable locking means for retaining the front cover 11 in closed position. This means comprises simply a pair of T-slots 20 formed in the front cover 11 in the lower edge thereof and opening through the lower edge thereof. These slots are spaced to correspond with the apertures 14 and, as best seen in Figs. 3 to 5, provide a plurality of tabs 21 which cooperate with the binding elements 17 to form the locking means for the front cover. If it is found desirable, in order to provide sufficient strength and life, the tabs 21 may be reinforced in some way.

As best seen in Fig. 4, when the front cover 11 is to be engaged with the binding elements 17, it is simply pressed onto the binding elements and as a result of the pressure so applied the tabs 21 are bent, as shown in Fig. 4, permitting them to pass by the ring members 18. After passing the ring members 18, the tabs, due to their resilient construction, straighten out and thus lock behind the ring members 18, as shown in Figs. 3 and 5. When so locked behind the ring members 18, the front cover 11 is so well secured that the weight of the leaves which have been turned and which are retained between the front and the back covers will not be sufficient to cause the cover 11 to open a distance sufficient to permit the leaves to drop down. When it is desired to turn a leaf, the front cover is simply pulled outwardly at its lower edge, at which time the tabs 21 will be bent oppositely to the manner shown in Fig. 4 and will permit disengagement of the tabs and the binding element. With the cover 11 disengaged, a leaf 12 is turned upwardly and positioned, as shown in Fig. 1, between the covers 10 and 11 and the front cover 11 is then again closed, and the tabs 21 pressed into engagement with the element 17 to lock the cover. It is believed apparent that for mailing purposes all of the leaves 12 are turned upwardly so as to lie between the covers 10 and 11, thereby making a compact mailing piece.

In view of the foregoing, it is believed apparent that I have perfected a new and improved calendar of the loose-leaf wall type and, more particularly, have perfected a new and improved binding and locking arrangement for such a calendar. When constructed in the manner disclosed herein, the leaves 12 are readily and quickly turned without removing the calendar from its supporting hook or without requiring much time or effort in the manipulation of fastening or securing means. Yet the construction provided herein assures that the leaves will be retained in turned position and will not fall of their own weight, and also assures that the calendar may be folded into a compact piece for mailing or preserving purposes.

70 I claim as my invention:

1. A calendar adapted to be suspended comprising a back cover, a front cover, a plurality of leaves, means providing a loose leaf binding arrangement suspending said leaves below said covers to be turned upwardly and concealed between

said covers as the leaves become obsolete and means including said last named means providing a locking arrangement for said front cover readily engaged and disengaged to permit turning of the leaves.

5 2. A calendar comprising a back cover, a front cover adapted to overlie said back cover and hingedly connected at its top edge to the top edge of said back cover and with its lower edge free of said back cover, said calendar being adapted to be suspended on a wall or the like, a plurality of leaves, means providing a loose-leaf binding arrangement suspending said leaves below said cover when the calendar is hung and permitting said leaves to be turned upwardly and concealed between said covers as the leaves become obsolete, and means formed on the lower edge of said front cover adapted to cooperate with said binding means to form a lock disengageable to permit turning of a leaf and insertion thereof between 20 said covers and engageable to retain the turned leaves between said covers.

3. A calendar comprising a back cover, a front cover adapted to overlie said back cover and hingedly connected at its top edge to the top edge 25 of said back cover and with its lower edge free of said back cover, an attaching means near the top edge of said back cover, a plurality of leaves, and a binding and locking arrangement comprising an aperture formed near the lower edge of said back 30 cover near each end thereof, a corresponding aperture formed near the upper edge of each leaf near each end thereof, a binding element threaded through the aperture in said back cover and through a corresponding aperture in said leaves 35 to suspend said leaves below said covers, and a keyhole slot formed in the lower edge of said front cover near each end providing tabs adapted to cooperate with said binding elements to form a disengageable locking arrangement for said 40 front cover by means of which said front cover may be secured to retain said leaves between said covers after they have been turned upwardly.

4. A calendar comprising a back cover, a front cover adapted to overlie said back cover and 45 hingedly connected at its top edge to the top edge of said back cover and with its lower edge free of said back cover, an attaching means near the top edge of said back cover, a plurality of leaves, and a binding and locking arrangement comprising 50 a pair of apertures formed near the lower edge of said back cover near each end thereof, a corresponding pair of apertures formed near the upper edge of each leaf near each end thereof, a binding element having two ring members each 55 threaded through one aperture in said back cover and a corresponding aperture in said leaves to suspend said leaves below said covers, and a pair of keyhole slots formed in the lower edge of said front cover near each end providing tabs adapted 60 to cooperate with said binding elements to form a disengageable locking arrangement for said front cover by means of which said front cover may be secured to assure the retention of said leaves between said covers after they have 65 become obsolete.

5. In a calendar of the loose-leaf type having a back cover, a front cover hingedly connected at its upper edge to the upper edge of the back cover with its lower edge free, and a plurality of leaves 70 smaller than said covers to enable the leaves to be placed between the covers and to be concealed when in that position, binding and locking means comprising an aperture formed in the back cover near each end thereof and adjacent the lower 75

edge thereof, an aperture formed in each leaf near each end thereof and adjacent the upper edge thereof, a binding element composed of a ring of resilient material having its ends normally overlapping to form a closed ring threaded through the aperture in the back cover and the aperture in the leaves to suspend the leaves below the cover, and a T-slot formed in the lower edge of the front cover near each end thereof, said T-slot providing resilient tabs adapted to interlock with said binding element to form a readily engageable or disengageable connection for the lower edge of the front cover.

6. In a calendar of the loose-leaf type having a back cover, a front cover hingedly connected at its upper edge to the upper edge of the back cover with its lower edge free, and a plurality of leaves smaller than said covers to enable the leaves to be placed between the covers and to be concealed when in that position, binding and locking means comprising a pair of apertures formed in the back cover adjacent the lower edge of the cover

and near each end thereof, a pair of apertures formed in each leaf similarly spaced from the top and end edge thereof as are the apertures in the back cover, a binding element for each pair of apertures comprising a ring member of resilient material threaded through one of the apertures in the back cover and one of the apertures in each of the leaves, and a connecting portion between said ring members, said ring members normally having their ends overlapping so as to provide closed rings, and a pair of T-slots formed in the lower edge of the front cover spaced from the ends of the cover a distance corresponding to the spacing of the apertures in the back cover, said T-slots providing a plurality of resilient tabs adapted to be readily engaged or disengaged from the binding element by the application of slight pressure to the lower edge of the front cover to provide a disengageable locking means for the lower edge of the front cover.
